UNITED STATES PATENT OFFICE

ROBERT M. MEISEL AND HARRY S. AIKMAN, OF PORT HURON, MICHIGAN

MOTION POSTER ADVERTISING DEVICE

Application filed September 21, 1931. Serial No. 564,060.

It is our knowledge that the art of producing animated motion posters is not new, in other words instead of stationary posters appearing upon vehicles or stationary objects of today, we provide a method whereby we use motion posters on vehicles and other moving objects for advertising purposes.

The outstanding feature of our invention or discovery is to put motion posters on vehicles and all other moving objects, and to accomplish this purpose we embody the use of a mechanism that is mounted upon a panel, and which is invisible to the observer, and the manner in which this mechanism will operate is for example:

A loaf of bread, a small boy upon one side of the panel, and a small girl upon the opposite side thereof, may be used as one form of advertising. The loaf of bread adapted to move from the boy to the girl, then to the boy again in regular intervals; the arms of the boy and of the girl to be induced to actuate in a manner so as to appear that the loaf of bread is being tossed from one to the other. The boy, girl and loaf of bread being formed of any suitable sheeting material. The mechanism may be actuated preferably by an electric motor mounted upon the panel in a concealed position, or in fact the source of power may be derived from a gasoline engine, or any other source available for the purpose, as the source of power does not affect the successful operation of the mechanism so long as there is adequate power provided. The mechanism is enclosed in a metal case weather-proofed with a glass front, and the said case being attached to the vehicle or moving object in a manner so as to render the same readily accessible and interchangeable.

It is not our purpose to confine our invention or discovery to any particular class of mechanism, such as chains, belts, cams, gears, rollers or the like, or to confine the objects or images upon the panel to be actuated by the said mechanism, to the combination of a loaf of bread, a small boy and girl as aforesaid, but it is the principle of applying motion posters to vehicles and all moving objects, that we seek protection by Letters Patent.

There are many combinations of images or objects and likewise the action of same, in fact the range is so unlimited that they would be too numerous to mention, however the same principle applies to one and all, and the same effect being the result of each combination.

Inasmuch as the particular process, method or system, whatever it may be termed, has not been heretofore used in the manner as we have herein set forth, to the best of our knowledge and belief, its application is unquestionably new and useful in the art of advertising, and must be admitted that it is a marked advancement and improvement over the old method of applying stationary posters to vehicles or moving objects or animated posters to stationary objects. This improvement lies in the fact that we carry animation a step further by embodying motion posters with a panel for vehicles and moving objects, which possesses a decidedly higher sense of appeal to human nature, and this being true, our invention or discovery is truly useful as well as being materially advantageous to the art of advertising.

With reference to the drawings:

Figure 1 is the front of the rear panel, clearly illustrating the complete mechanism of the device, and indicating the movement thereof by a series of dotted lines.

Figure 2 is a view of one end of the guide member for loaf of bread, and showing how it is connected to the rear panel of the device.

Figure 3 is a sectional view of one of the adjustable stop members for limiting the travel of the pivotal beams.

Figure 4 is a front elevation of the device, and what it exposes to view, and broken as indicated.

Figure 5 is an enlarged section of one end of the case with mechanism removed.

The illustration comprises a complete weather-proof case, which is preferably composed of metal back 1, and with particular reference to Figure 5 it is clearly seen that metal side enclosures 2 are provided. The entire front of the case is enclosed by glass 3, which is adequately supported by metal members 4, also felt padding 5 where indicated.

Members 4 are adjustable to glass 3 by means of screw 6 through an elongated slot in sides 2 and members 4.

Front panel 7 and rear panel 8 are provided, both of which are preferably of wood, and still referring to Figure 5 it is observed that wood bottom 9 forms a separator for the said panels. Panel 7 being secured to bottom 9 by a plurality of screws 10, while panel 10 8 is connected to bottom 9 by bolts 11, with the usual nuts therefor, and recessed portion 12 in bottom 9 for the head of the said bolts which pass through the said bottom as indicated. The panel formation is rigidly supported on members 4 by brackets 13, which are secured to the underneath surface of bottom 9 by screws 14. Sides 2 are formed as at 15, which are respectively secured to the upturned edge 16 of back 1 and are retained 20 in this position by bolt 17 with nut 18, the latter being locked in the position as shown. Lug 19 is secured to portion 15 of sides 2 for the purpose of connecting the respective ends of panel 8 by screws 20, which engage 25 threaded holes in the said lug respectively.

The case of the device having been described, the operation of the mechanism immediately follows:

Referring to Figure 1, it is seen that the 30 entire mechanism of the device is mounted upon rear panel 8, and the source of power is through electric motor 21, which is supported by frame 22 with suitable bearings within the said frame. Frame 22 is connected to an 35 additional frame 23 by the usual bolts, and this frame is secured to block 23A by bolts 23B, and the said block secured to panel 8 by bolts 23C. Upon the opposite side of panel 8 is block 9A, and is secured to the said 40 panel by bolts 9B and screws 9C as indicated. Line shaft 24 is provided, with bearings 25 and is supported on one end by upright 26, also loose coupling 27 upon the said shaft as shown. Worm 28 on shaft 24 engages gear 45 29, and the said gear journaled in bearings within sub-frame 30, also sprocket 31 secured to gear 29 for the purpose of driving sprocket 32 by chain 33. Sprocket 32 is suitably journaled to panel 8. Lever 34 is provided, 50 to which is secured by the usual rivets, member 35, and the latter being metal cut in the likeness of a loaf of bread. Lever 34 is pivotally mounted upon stud 36, and the said stud connected to panel 8, lever 34 also forms 55 offset 37 in order that member 35 may extend to align with the front surface of panel 7, and is adapted to swing from one side of the case to the other, as the dotted lines indicate by means of link 38, one end of which is 60 pivotally secured to lever 34 and the opposite end thereof pivotally secured to sprocket 32. Slot 39 in the said sprocket is for adjusting the travel of member 35.

In order to properly balance lever 34 at 65 all times during the operation thereof, a plu-

rality of coil springs is provided, and one end of all of the said springs secured to the said lever where indicated. The opposite end of springs 40 are respectively secured to members 41, while the opposite end of springs 42 are connected to oscillating members 43.

Guide member for lever 34 comprises arched rods 44, between which the said lever travels, and with reference to Figure 2 it is clearly seen that the ends of the said rods are formed at right angles thereto, are threaded and connected to panel 8 by adjusting nuts 45.

Referring to Figure 4, front panel 7 is formed as indicated by line 46, and forms portion of boy 47 and girl 48 above dotted line 49, while below this line the remainder of the images 47 and 48 is painted upon panel 7. In this manner the view presented by the invention is the appearance of member 35 being tossed from the boy to the girl and vice versa. The space for advertising matter is suggested as indicated.

The arms of images 47 and 48 will be actuated slightly to give the appearance of a tossing motion. Both of each of the said images will operate at different intervals, but as a single unit, and are adapted to pivot at 90 points indicated at 47A and 48A respectively.

Again referring to Figure 1, the upper end of upright link 50 is connected to the arm unit of image 47 and through link 47B, similar link 51 is likewise secured to arm unit of image 48 through link 48B. The lower end of links 50 and 51 are pivotally secured to horizontally disposed beams 52 at 53 respectively, and the said beams adapted to be pivotally secured to members 54 respectively. As lever 34 swings to the right or to the left stud 55, which is permanently fixed on the same, will strike cushion spring 56, one of which is secured to the end of beams 52 by rivet 57, thus driving either of links 50 and 51 upward, simultaneously actuating the arm unit of the respective images 47 and 48. Coil springs 58 are for the purpose of returning links 50 and 51 to their normal position as shown.

The travel of the arm unit of the said images is adjustable at 59 upon links 50 and 51. Referring to Figure 3, forked members 60 are provided for the purpose of adjusting the travel of beams 52, and the said members having a threaded shank in order to secure the same to panel 8 by nut 61, also adjusting screw 62 as indicated.

Having thus described our invention or discovery, what we claim as new is:

1. In a device of the character described, an enclosed case for the same, a vertically arranged front panel adapted to be secured within the said case, a similar formed rear panel within the said case, means upon the said front panel whereby the arms of a girl 125

and a boy respectively will actuate in a manner so as to appear that the boy and girl are tossing a loaf of bread to one another, the boy upon one side of the panel and the girl 5 upon the opposite side thereof and in face to face relation, the aforesaid means also actuating the said loaf of bread.

2. In a device of the character described, an enclosed case for the same, a front panel 10 and a rear panel within the said case, the image of a boy and girl upon the said front panel with arms pivotally secured thereto respectively, an image of a loaf of bread intermediate the said boy and girl, means for 15 actuating the said loaf of bread in alternating movement from the boy to the girl and from the girl to the boy appearing that it is being tossed in this manner, and this means comprising a lever pivotally secured to the 20 front of the said rear panel, the image of the bread secured to the upper end of the said lever, the combination of an electric motor upon the said panel, a horizontal shaft secured to the said motor, a worm secured to 25 the said shaft to engage a gear beneath the same, a sprocket connected to the shaft upon which the said worm is secured, an additional sprocket engaging the first-named sprocket by a chain, a pivotally secured link connecting the last-named sprocket with the lower 30 end of the aforesaid lever, a plurality of balancing springs for the device, one end of a portion of the said springs secured to the lower part of the said lever and one end of 35 the remaining springs secured to a higher portion of the said lever and the opposite end of all of the said springs secured to pivotally mounted members that are secured to the aforesaid panel respectively.

3. In a device of the character described, an enclosed case for the same, a front panel and a rear panel within the said case, the image of a boy and girl upon the said front panel, both arms of the said boy and girl 45 pivotally secured thereto, a lever pivotally secured to the said rear panel, means whereby the said lever will actuate the arms of the said images in a manner so as to appear that they are tossing an image of a loaf of bread 50 to one another, the said bread image being connected to the upper end of the said lever, and this means comprising a complete unit of mechanism for the said boy and a similar unit for the said girl, and the said units consisting of a horizontally arranged beam pivotally secured near the center thereof to the 55 said panel, a stud secured to the said lever and adapted to strike one end of the said beam simultaneously driving the opposite 60 end of the said beam upward, a vertically arranged link one end of which is pivotally connected to the last-named end of the said beam, and the opposite end of the said link pivotally connected to an additional short 65 link, and the opposite end of the last-named

link being fixed with the arms of the aforesaid boy and girl respectively, means upon the aforesaid beam for limiting the movement thereof, also means consisting of a spring secured to the bottom of the aforesaid case and to the end of the said beam having the said vertical link connected therewith.

In testimony whereof we hereunto affix 75 our signatures.

ROBERT M. MEISEL.
HARRY S. AIKMAN.
